CLAIM

The ornamental design for a storm shelter body, as shown and described.

DESCRIPTION

FIG. 1 is a perspective view.

FIG. 2 is a right side view.

FIG. 3 is a top view.

FIG. 4 is a front view.

FIG. 5 is a perspective sectional view along lines 5-5 from FIG. 1.

FIG. 6 is a sectional left side view along line 6-6 from FIG. 3.

FIG. 7 is a sectional view along line 7-7 from FIG. 3; and, FIG. 8 is a sectional view along line 8-8 from FIG. 3.

The broken line showing is included for the purpose of illustrating portions of the article and forms no part of the claimed design.
